CALCULATING MACHINE

Wells A. Webb, Berkeley, Calif., assignor to
Marchant Calculating Machine Company, a cor-
poration of California

Application September 26, 1931, Serial No. 565,234
Renewed March 22, 1938

11 Claims. (Cl. 235—63)

The present invention relates to devices comprising a stationary part and a displaceable part and particularly to mechanism for selectively shifting the displaceable part in either direction 5 to any desired position.

The invention is shown and described as applied to a calculating machine, but is equally applicable to adding machines, printing machines, typewriters, listing machines, check 10 writers, tabulating machines and other devices having relatively movable parts which it is desired to position in various displaced positions with respect to each other.

It is an object of the invention to provide 15 means for automatically positioning a displaceable mechanism to a predetermined position.

Another object of the invention is to provide means for automatically shifting a displaceable mechanism to any one of a plurality of predetermined positions under the control of means 20 adapted to determine the direction and the extent of movement of said mechanism.

Another object of the invention is the provision of means for locking the displaceable 25 mechanism in any displaced position thereof, said means comprising the driving means.

Another object of the invention is the provision of means for automatically shifting a displaceable mechanism including unitary controlling 30 means settable to a plurality of positions to control operation of said shifting means.

A further object of the invention is the provision of suitable spring power for shifting a displaceable carriage through one or more positions 35 in either direction upon operation of the controlling means therefor.

Another object of the invention is to provide suitable means for positively arresting a displaceable carriage at the completion of a shift 40 without causing undue strain on the shifting mechanism.

Other objects will appear from the following description, reference being made to the drawings, in which:

45 Figure 1 is a general plan view of the tabulating shift comprising the present invention.

Figure 2 is a front elevation of the special shift keys and associated mechanisms.

Figures 3, 4, and 5 are sections taken on lines 50 3—3, 4—4 and 5—5, respectively, of Figure 1 illustrating the various instrumentalities employed in the present invention.

Figure 6 is a fragmentary detail in plan of the mechanism which controls the direction as well 55 as the extent of a shifting operation.

Figure 7 is a section taken on line 7—7 of Figure 2 showing in detail the differentially movable slide for determining the order into which the carriage of a calculating machine is to be 60 shifted and the bail for holding said slide and

parts controlled thereby in its displaced position until automatically released and restored at the termination of a shifting operation.

Figure 8 is a fragmentary section through the parts constituting the unit for connecting an air shock absorber with the driving or actuating means of the carriage during the last step of a shifting operation thereof. 5

Figure 9 is a detail view of the cam lever which prevents operating connection between the air 10 shock absorbing means and the carriage actuating means until the last step of a shifting operation.

Shift keys

The shifting mechanism is controlled by a 15 plurality of shift keys 1 which are preferably arranged in one single row directly in front and in alignment with the various key sections forming the keyboard of a calculating machine.

The shift control keys (Figures 1 and 2) are 20 mounted in a key section frame 2 of conventional design and are held in normal or raised positions by compression springs 3. Disposed underneath the key stems 4 and mounted in brackets 5 depending from the key section frame 2 is a slide 25 6 with a plurality of V-notches 7 which are identical to each other, there being one of these notches provided for each shift key stem 4. At the bottom of each V-notch is a downwardly extending slot 8 conforming to the thickness of 30 the shift key stems. The distance between the center of each of these slots is the same, but is slightly greater than the distance from key stem to key stem so that in the relative spacing between the key stems and the slots each succeeding slot 8 is spaced one increment further away from its respective key stem than the preceding one, so that depression of a shift key will position the said slide 6 a differential amount equivalent to the value of the key depressed. A strong 35 spring 9 tensioned between a stud 10 on the slide 6 and a depending lug 11 on the shift key frame always tends to return the slide 6 and all other parts controlled thereby to normal or inactive 40 position. The extreme left hand end of slide 6 is provided with a downwardly extending portion 45 which terminates in a pin 12. This pin provides the connection between the slide 6 differentially positioned by any of the shift keys 1 and the mechanism for controlling the extent of a shifting operation. 50

A bail 13 (Figures 1, 2 and 7) positioned directly behind said slide 6 and underneath the shift key stems 4, is journaled at 14 in the rearwardly extending arms 5a of brackets 5 on the key section frame 2. Whenever a shift key is depressed not only the slide 6 is positioned thereby, but also the bail 13. However, the timing of operation of these two parts 6 and 13 is such that the bail 13 is not rocked downwardly until the key stem has 55 60 65 60

fully positioned slide 6 and has come into alignment with a slot 8. The moment this happens the respective key stem will have contacted the bail 13 and further downward movement of the 5 key stem 4 will impart rocking movement to said bail 13. At its left hand end, said bail is provided with a rearwardly extending right angular projection 15, while at its right hand end (Figures 1, 2 and 7) it has a depending arm 16, the purpose 10 of which parts will be described as the specification progresses.

Selective shift control

The mechanism which is set by depression of a 15 shift key 1, through the medium of slide 6, to determine the distance of the carriage shift comprises a two-armed lever 21 (Figures 1 and 6) fulcrumed at 22. The forward arm 21a of this lever embraces with its slot 23 the pin 12 of the 20 slide 6, as already mentioned, while the rearward arm 21b carries a stud 24 which projects through a slot 25 of a bell crank lever 26 pivoted at 27 underneath and to the carriage guide plate 28. The forward extremity 26a of this bellcrank is 25 provided with an arcuate rack 29, normally positioned to the left side and in the path of projection 15 on bail 13 while the rearward and shorter arm 26b of said bellcrank engages with a pin 30 in the longitudinal slot 31 of a lever 32 which by 30 means of another longitudinal slot 33 in alignment with the first one, embraces the fulcrum 27 of bellcrank 26 for limited universal as well as longitudinal movement in opposite directions. In examining Figure 4 of the drawings it will be 35 noted that lever 32 normally touches with its entire upper face the underside of carriage guide plate 28, but is spaced away from the short arm 26b of bellcrank 26 by means of a sufficiently strong compression spring 33a surrounding the fulcrum pin 27. The other enlarged end of lever 40 32 is supported for sliding movement by a spring biased two-armed lever 34 (Figures 1 and 4) pivoted at 35. Thus it is apparent that by virtue of its peculiar mounting, lever 32 is not only capable of longitudinal adjustment in opposite directions, 45 but also capable of limited vertical and radial movement about its fulcrum point 27.

Lever 32 is also equipped on the upper side of its free and enlarged end with a lug 36 which is in direct alignment with the center line bisecting 50 fulcrum 27 and pin 30 (Figures 1 and 6). Lug 36 is adapted to cooperate with a plurality of steps 37 attached to the underside of the carriage plate 38, there being one of such steps provided for each order into which the carriage (not 55 shown) can be shifted.

The normal position of lever 32 and lug 36 is illustrated in full lines in Figure 6, in which position said lug is out of the path of steps 37. When a shift key is depressed the lug 36 is adjusted in a 60 counter-clockwise direction a differential amount corresponding to the value of the depressed shift key 1 through the medium of slide 6, pin 12, two armed lever 21, bellcrank lever 26 and lever 32 to which it is attached. The lug 36 is illustrated 65 in dotted lines in Figure 6 in the position to which said lug is moved upon depression of the "1" shift key which determines a shifting of the carriage to its extreme left hand position.

This mechanism whereby lug 36 may be selectively positioned in the path of transverse movement of any of the steps 37, constitutes a means for forming a series of mechanical representations corresponding to the respective positions of the carriage, because in each of the positions to which 70 lug 36 may be set, the mechanism controlled

thereby will cause the carriage to be arrested when it reaches a different position corresponding to that mechanically represented by the setting of the lug positioning mechanism.

Means are provided for maintaining the adjustment given to the shift controlling lever upon depression of a shift key until the carriage shifting operation has progressed to a point where the carriage is shifting into the respective order predetermined by the depressed key. 10

In order to maintain such adjustment of lug 36 for the period mentioned above, bellcrank 26 is equipped with an arcuate rack 29 (Figures 1, 2 and 6) at its extreme forward end, as already described, and bail 13 is provided with a rearwardly 15 extending projection 15 which is capable of cooperating with a plurality of notches 29a formed within arcuate rack 29, there being one of such notches 29a provided for each shift key 1; i. e. each ordinal position of the carriage. 20

Thus whenever a key 1 is depressed by the operator, the arcuate rack 29, which normally lies to one side of projection 15, as can be seen in Figures 1 and 2, is moved in counter-clockwise direction by virtue of its connections 12, 21, 24 with slide 6, an amount determined by the movement of the latter caused by the respective depressed shift key stem 4. Such movement brings the proper notch 29a directly underneath and into alignment with rearwardly extending projection 15 on bail 13. The first and longer part of the downward movement of a key stem 4 when being depressed is utilized entirely for differentially positioning slide 6, and for bringing all 30 cooperating parts thereof to their predetermined 35 locations, this being accomplished while the key stem 4 is sliding over the cooperating inclined surface of notch 1. The moment the key stem has moved over this inclined surface and into alignment with slot 8, the second and shorter part 40 of the downward stroke of key stem 4 commences. The key stem 4 now contacts the top edge of bail 13 and further downward movement thereof causes bail 13 to rock about its pivot points 14 sufficiently to bring projection 15 thereon into engagement with the aligned notch 29a, thus locking 45 securely parts 6, 21, 26, 32 and lug 36 in their selected positions while the respective key 1 is maintained in such depressed position.

Bail 13 is maintained in depressed position 50 during a shifting operation after release of the depressed key by coil spring 52 (Figures 1 and 7) which is normally restrained but which is permitted to become effective during a shifting operation by the following mechanism. As mentioned previously, bail 13 is provided at its right hand end with a downwardly extending arm 16 (Figures 2 and 7) which abuts the extreme end of the long arm 41a of a bellcrank 41 which is fulcrumed on a suitable support at 42. The shorter arm 41b of this bellcrank lever 41 carries a stud 41c which penetrates an elongated slot 43a within the forward arm 43b of a two-armed lever 43 pivotally supported at 44. The other arm 43c of lever 43 is curved and its free end normally abuts a right angular extension 45a of an arm 45 (Figures 1 and 3) which is attached to a sliding member 46 at 47 for limited pivotal movement thereon. The member 46 in turn is slidably secured to a bracket 49 depending from the carriage guide plate 28, by means of pin and slot connections 48. On its extreme left hand end slide 46 is equipped with a lip 46a which is adapted to be engaged by a latch 53 also slidably attached to bracket 49 and normally maintained 75

in its uppermost position by a tension spring 50.

Members 45 and 46 are constantly urged towards their extreme right hand or normal position, as shown in Figure 3, by a spring 51 which is stronger than spring 52 and which is tensioned between right angular extension 45a and a convenient place on the machine frame (not shown). In this position members 45 and 46 hold bail 13 in its inoperative position as shown in Figures 1 and 7 through the medium of two-armed lever 43 and bellcrank 41, despite the influence of coil spring 52, the strong tension spring 51 being easily able to neutralize the action of said coil spring 52 which tends to rock bail 13 with its lateral extension 15 into engaging position with rack 29. Whenever a shift key 1 is depressed, it is therefore necessary to remove the restraining influence from the coil spring 52 in order to permit it to act upon bail 13 and thereby lock any setting of lug 36 for the entire duration of a shift independent of the release of the depressed shift key by the operator. This is accomplished by latch 53 which is always in a condition to latch slide 46 whenever it is pushed to the left, against the tension of spring 51, by depression of any of the shift keys 1 and through the medium of bail 13, bellcrank 41 and two armed lever 43. The moment such action has taken place and slide 46 (Figure 3) is latched, all pressure is removed from lever 43 and 41 and coil spring 52 will act of its own accord to maintain bail 13 and extension 15 thereon in operative position until slide 46 is again released by automatic means to be described hereinafter.

Shift direction control

The direction of a carriage shift is determined by a very simple mechanism to be described presently which functions entirely automatically, making it unnecessary for the operator to set a special shift direction key before depressing any of the shift keys 1. This mechanism is largely controlled by two important factors. One is the carriage position at the time the operator depresses a shift key; and the other of course is the ordinal number of the shift key depressed.

It has already been mentioned under the heading of "Selective shift control" how lever 32 and lug 36 are capable of a limited angular adjustment about fulcrum point 27 to bring the lug 36 into the shifting path of any of the nine steps or ridges 37 on the underside of the carriage support plate 38 (Figures 1, 4 and 6). Such adjustment of lever 32 and the extent thereof is of course controlled by the respective shift key depressed, as has been explained under the above heading.

Each ridge 37 represents one of the nine orders of the machine to which the carriage may be shifted, the length of each ridge corresponding to the distance between each order and consequently to a single shift. The furthest right hand step or ridge 37 represents the first order, or extreme left hand position of the carriage, while all steps to the left thereof represent the higher orders up to nine.

In Figures 1 and 6 the carriage plate 38 is shown in the #6 order, while lug 36 is shown in its initial or zero position. The upper end of lug 36 is chamfered and extends through an appropriate aperture 28a in the carriage guide plate 28 (Figure 1) into the plane of ridges 37 and is held in such position by spring biased two-armed lever 34 (Figure 4) pivoted at 35 to a bracket 40 attached to 49, as has already been explained

under the heading of "Selective shift control." The right hand end of lever 34 underlies a nose 45b riveted or welded to member 45 and disposed opposite thereto is a similar nose 61a carried by a two-armed rocking lever 61 also pivoted at 35, 5 the tip of nose 61a being positioned slightly above the tip of nose 45b. The other and somewhat shorter arm of lever 61 is slotted at its end and is engaged by the forward and pin shaped end 62a of a shifting fork 62 (Figures 1 and 4) 10 which is pivoted at its approximate center to a rearwardly extending lug 63a formed on a bracket 63 depending from the carriage guide plate 28. The other fork shaped end 62b (Figure 5) of shift fork 62 engages a slidable clutch member 15 64 on a vertical shaft 65, the lower end of which is supported by a suitable thrust bearing 66, while the upper end of said shaft extends through the plate 28 for perfect vertical alignment and carries on its square end 65a which extends above 20 the plate 28 a small drive pinion 67 constantly in mesh with the teeth of the rack 38a formed on the rear edge of said carriage plate 38 for shifting the same in either direction.

The clutch member 64 is keyed to shaft 65 25 for limited sliding movement by means of a pin 68 which extends through the slot 69 in shaft 65. The two ends of clutch member 64 are each equipped with two ratchet teeth 70 and 71 which normally mesh with complementary ratchet teeth 30 72 and 73 on the sleeves 74 and 75 respectively. The upper sleeve 74 is keyed to the splined hub of a bevel pinion 76, while the lower sleeve 75 is keyed to the splined hub of a bevel pinion 77. Both of these bevel pinions are freely 35 rotatable on the shaft 65. Retaining rings 78 and 79 prevent said sleeves from sliding off of the hubs of said bevel gears 76 and 77 inasmuch as they are always spring pressed towards clutch member 64 by the compression springs 80 and 81 40 surrounding said hubs. Bevel pinions 76 and 77 in turn are in constant mesh with a larger bevel gear 82 which is directly connected to the shift actuating mechanism, to be described in a succeeding part of this specification, and therefore 45 constitutes the driver of this bevel gear assembly 76, 77 and 82. The ratio of the gear assembly is such that gears 76, 77, shaft 65 and gear 67 rotates through ninety degrees for each ordinal displacement of the carriage. 50

As heretofore explained, when a shift key 1 is depressed by the operator the locking assembly comprising the parts 45 and 46 is pressed towards the left by the members 13, 41 and 43 and this movement of slide 46 and arm 45 pivoted thereto 55 is utilized to shift the clutch member 64 out of engagement with one or the other of the two sleeves 74 and 75 in order to establish a driving connection between either one of the two bevel pinions 76, 77 and the larger bevel gear 82 60 for driving through the shaft 65 the drive pinion 67 and consequently the carriage support plate 38 in either direction, depending on which one of the two bevel pinions 76, 77 is being driven and which one is idling. However, as long as the 65 clutch members 64, 74 and 75 are in their neutral or ineffective positions, as illustrated in Figure 5, the entire gear assembly remains locked against any rotation whatsoever. It should be noted that the drive assembly can not lock itself against 70 rotation except when the carriage is properly positioned, as, after the drive is initiated, gears 76 and 77 must rotate for ninety degrees each before the complementary ratchet teeth become effective to stop the drive. The two-armed le- 75

ver 61 is always urged to the position in which this clutch member 64 is in such ineffective or neutral location by a strong spring biased centralizer 83 (Figure 4) which engages with its V-notch a pin 84 on lever 61. This centralizer 83 is pivoted to the bracket 49 depending from plate 28 at 85 and is pulled in clockwise direction by the spring 85a tensioned between a convenient pin (not shown) on the base plate of the machine and a pin 86 on the lower extremity of 83.

It is thus apparent that in order to shift clutch member 64, either upwardly or downwardly, it is necessary to rock two-armed lever 61 either in clockwise or in counter-clockwise direction. When rocked in a clockwise direction, lever 61 and shift fork 62 move clutch member 64 downwardly to remain in driving engagement with bevel pinion 77 and out of engagement with the bevel pinion 76, and conversely when lever 61 is rocked in a counter-clockwise direction, shift fork 62 shifts clutch member 64 upwardly to remain in driving relationship with pinion 76 and entirely out of engagement with pinion 77. From the foregoing it is apparent that when lever 61 is moved from the position shown in Figure 4 one of said pinions is being driven by gear 82 to rotate clutch member 64 and consequently the shaft 65, gear 67, and through rack 38a shift the carriage (not shown) while the other pinion rotates idly.

Means are provided for positioning a controlling member to determine the direction of shift in accordance with the shift key depressed. For convenience the ordinal positions of the carriage are numbered from 1 to 9 starting with the extreme left hand position so that movement of the carriage to the left is to a lower order position and vice versa. As illustrated in the drawings, the carriage or carriage plate 38 is in the #6 position; if it is desired to shift to the #1 position the operator depresses the #1 shift key and the lug 36 is thereby moved from its zero location to the #1 location indicated by the dotted lines in Figure 6. During such movement lug 36 moves over the #6 ridge with the result that arm 32 is momentarily depressed at its left hand end, which carries the lug 36 and such movement causes a similar movement of lever 34 (Figure 4) in counter-clockwise direction about pivot point 35 against the tension of spring 39 with the result that the right hand end of lever 34 underlying nose 45b on arm 45 raises the latter sufficiently to bring the point of its nose above the point of the nose 61a on 61 so that subsequent movement of arm 45 towards the left brings the lower edge of nose 45a on top of nose 61a, therewith forcing the entire lever 61 to rock in clockwise direction to shift clutch member 64 out of engagement with the upper bevel pinion 76 to establish a drive of shaft 65 through bevel gear 77, causing carriage plate 38 to shift five orders in the left hand direction.

If on the other hand it is desired to shift from the #6 order in which the carriage is, into the #9 or #8 order, then lug 36 does not move over a ridge 37 but is moved from the zero position, in which it is shown, one or two increments in counter-clockwise direction and into the shifting path of the #9 or the #8 step 37 and the two-armed lever 34 remains stationary during such procedure so that the point of nose 45b remains, as shown in Figure 4, below the point or apex of two-armed lever 61. In that case, subsequent movement of arm 45 towards the left

would bring the upper edge of nose 45b below nose 61a, forcing the latter upwardly to rotate the entire lever 61 in counter-clockwise direction and by means of the shift fork 62 shift clutch 64 out of engagement with bevel pinion 77 so that the shaft 65 would be driven in the opposite direction by bevel pinion 76, causing the carriage to be shifted towards the right. Arm 45 can only yield in a counter-clockwise direction about pivot 47 on account of a slotted stud 87 (Figure 10 3) on bracket 49 and is normally always held in contacting position with said stud by tension spring 51.

Since the timing must be such that the selective shift control takes place before the lock 15 therefor is set, as is apparent when viewing Figure 2, and as has already been thoroughly explained, means are provided for latching arm 45 with its nose 45a in raised position long enough to permit its point to locate on top of the point 20 of nose 61a upon the subsequent movement to the left of arm 45 caused by the rocking of bail 13, bellcrank 41 and two-armed lever 43. This is of course only necessary when during the course of a shift selection the lug 36 has been 25 moved over one of ridges 37.

The mechanism provided for this purpose comprises a latch hook 88 (Figures 1 and 3) pivotally mounted to a bracket 89 on the underside of plate 28. A spring 90 tensioned between a central point on latch hook 88 and the bracket 49 tends to hold the hook 88a normally in contact with the forwardly extending right angular projection 45a of arm 45. The moment arm 45 is raised by lever 34, hook 88a will immediately 35 latch the arm in such raised position, holding it there until the entire arm 45 is pushed towards the left by lever 43. Latch hook 88 follows the movement of arm 45 sufficient distance to permit the point of nose 45b to locate on top of nose 61a. Further movement of arm 45 causes latch hook 88 to disengage from projection 45a due to the contacting of stop 88b (Figure 3) with the plate 28 just after nose 45b is positioned on nose 61a. A pin 91 on bracket 49 is provided to 45 limit the upward movement of arm 45 in order to prevent clutch 64 from shifting out of its proper position during the shifting operation and until again released by slide 46. This happens at the end of the shifting operation when slide 50 46 and arm 45 are automatically released to return to their normal or initial position and all the parts controlled thereby are free to again assume the positions shown in Figures 3 and 4 of the drawings.

55

Shift actuating mechanism

The actuating or motive power for driving the large bevel gear 82 (Figures 1 and 5) which transmits its motion to the clutch member 64 through either one of the two bevel gears 76 or 77, as already described in the preceding chapter, comprises an ordinary clock spring 96 enclosed in a suitable housing 97. The inner end of this spring is fastened to the shaft 98 upon which both the gear 82 and the spring housing 97 are rotatably mounted, while the outer end of said spring 96 is attached to the housing 97. The housing in turn is rigidly secured to the hub of bevel gear 82 so that these parts always rotate 70 in unison whenever clutch member 64 is shifted out of its neutral position. The spring 96 has sufficient force to shift the accumulator carriage of a calculating machine through the maximum number of orders, when properly wound up and 75

after such a shift of the carriage through all the orders there is still enough reserve force left in the spring to complete another shift if necessary.

- 5 Automatic means are provided for winding said clock spring during the first cycle of movement of the actuator that occurs after a shifting operation. This means comprises an ordinary friction clutch 99 made up of two discs 100 and 101. 10 Disc 100 is formed integral with the shaft 98, while the disc 101 is keyed to a second shaft 102 carrying the drive gear 103 which is driven by the actuator through a convenient train of intermediate gears (not shown). In order to maintain 15 discs 100 and 101 in constant frictional engagement with each other, a compression spring 104 is interposed between the disc 101, slidably keyed to the shaft 102, and two lock nuts 105, 106 by means of which the amount of compression of 20 said spring 104 may be varied. The two lock nuts 105 and 106 fit on a threaded portion 107 on shaft 102 and are in juxtaposition to the drive gear 103 which is keyed to the shaft for perfect alignment with the train of intermediate gears 25 to the actuator (not shown) by a pin 108. The entire assembly is properly supported in bearings 109 and 110, attached in any suitable manner to an upright support plate 111 on the base plate of the machine.
- 30 It is thus apparent that with the proper ratio between the intermediate gears (not shown) and the gear 103, the first cycle of movement of the actuator after any shift is sufficient to wind up clock spring 96 through the medium of friction 35 clutch 99, inasmuch as said spring is anchored to shaft 98 with one end and to the stationary housing 97 with the other end. During all subsequent actuation cycles disc 101 will merely slip over disc 100 without rotating the latter, the 40 spring 96 having already been wound up during the first cycle of movement of said actuator. The spring is thus maintained in a constant state of tension in readiness to actuate the shifting mechanism whenever a shift is determined.
- 45 Means are provided for locking the carriage plate in any displaced position thereof. Said means are controlled by the slide 46 (Figure 3) and comprise two dogs 112 and 113 which are slidably mounted on the front face of bracket 49 (Figures 1 and 3), and which are normally 50 spring pressed into engagement with appropriate rectangular shaped and equally spaced apertures 38b in the carriage plate 38 by the compression springs 114 and 115 which are anchored between 55 the lower extremities of dogs 112, 113 and lugs 49a and 49b formed in the bracket 49. The dogs are disengaged from the plate 38 upon depression of a shift key 1 by slide 46 in order to permit the shift actuating mechanism to function.
- 60 To accomplish this, slide 46 is equipped with a cam face 46b (Figure 3) which cooperates with a pin 116 on a sliding member 117, also mounted in a groove cut into the bracket 49 midway between the dogs 112 and 113, as can be clearly seen in Figure 1 of the drawings. A suitable strip of metal riveted to the front of bracket 49 retains these three slidable members 112, 113 and 117 in their respective grooves.
- 65 A pin 118 on slide 117 projects through a slot 119 in bracket 49, just as pin 116 projects through a similar slot 120 for limiting its vertical movement. The pin 118 also projects through slots in a pair of bars 121 and 122 of equal dimensions which are pivoted at opposite points 123 and 124 to the bracket 49. The whole unit forms a con-

venient toggle joint arrangement for exerting an equal and simultaneous pressure upon the two pins 125 and 126 on dogs 112 and 113 respectively when the slide 117 is pulled downwardly by the cam 46b on slide 46. The moment this happens 5 carriage plate 38 is free to move in either direction, depending on which one of the bevel pinions 76 and 77 (Figure 5) is driving, and this condition obtains as long as slide 46 is latched by latch 53; the moment the latter is released, 10 however, dogs 112 and 113 will immediately be pressed into engagement again by springs 114 and 115 with two of the apertures 38b in plate 38 to arrest the latter in its movement.

Shift stopping mechanism

15

In order to release the slide 46 at the proper moment to stop the carriage plate 38 in the selected ordinal position, means are included in the construction of this shifting mechanism 20 which will not only function to disengage latch 53 from slide 46 at the proper time, but will also function to decrease the speed of the carriage shift plate 38 when shifting into its home position to prevent undue strain on the working parts 25 of the shifting mechanism.

The stopping mechanism about to be described is actuated by the arm 32 (Figures 4 and 6) during its movement to the left or right caused by the lug 36 contacting with one of the steps or 30 ridges 37 just before the completion of a shift. If the carriage happens to be shifting towards the left from a higher into a lower order, arm 32 is pushed by the respective step 37 to the left as the carriage enters the selected position, and 35 conversely if the carriage is shifting towards the right from a lower order into a higher order, arm 32 is pushed an equal distance towards the right. Its elongated slots 31 and 33 surrounding the pins 30 and 27 respectively permit such movement in opposite directions to the extent of a distance equaling the space between two orders, 40 as has already been explained in a preceding part of this specification.

This lateral movement of arm 32 in either 45 direction is utilized to rock an upright lever 131 which is pivoted at 132 to a small bracket 133 fastened to the base plate 134 of the machine. On its extreme upper end is a pin 135 (Figures 1, 4 and 6) which projects through a radial slot 50 136 in member 32. By means of this pin 135 arm 32 is normally held in its centralized position in which lug 36 can pass over only one of the ridges 37 during its adjustment by any of the shift keys 1. Of course, rocking lever 131 must 55 also be maintained in such centralized position at all times except when it is rocked by arm 32 to operate the shift stopping mechanism.

For this reason a centralizer 137 (Figure 4) is provided which is keyed to a shaft 138 journaled at its forward end in bracket 49 and at its rearward end in bracket 63. Centralizer lever 131 carries at its free end a pin 139 which normally engages the bottom of a V-shaped aperture in rocking lever 131 tending to hold the latter always in absolutely vertical position by virtue of a strong spring tensioned between a suitable point on centralizer 137 and the pivot point 132 of lever 131. Keyed to the other end of shaft 138 is a lever 140 (Figures 3 and 4) which rests 60 with its free end on a lip on latch 53, so that whenever the lever 131 is rocked by sliding movement of arm 32 as the carriage enters the selected position, lever 140 is also rocked through the medium 65 70 75

of shaft 138 to which both levers 137 and 140 are keyed, with the result that latch 53 is pulled down and out of engagement with projection 46a on slide 46 to permit the latter to be pulled back to 5 initial position by its strong tension spring 51. Such movement of slide 46 immediately removes the pressure of cam 46b from the pin 116 on slide 117 so that the compression springs 114 and 115 are free to expand again pushing dogs 112 and 10 113 into locking engagement with the proper apertures 38b in plate 38, thus stopping the latter in its shifting movement.

In order that the dogs 112 and 113 may engage the carriage plate 38 to arrest the latter without 15 undue strain in the position determined by the depressed shift key 1, a double acting air compressor 141 (Figures 1 and 5) is provided by means of which the speed of the carriage plate 38 can be slowed down during the last step of the 20 shift. This compressor is supported by upright member 111 (Figure 1) and is of conventional design, comprising a cylindrical housing 142 (Figure 5) closed at both ends within which a piston or plunger 143 is reciprocated. Piston 143 is operated by shaft 147 through connecting rod 144 journaled on crank pin 146 supported between 25 crank arms 145 and 145'. Crank arm 145 is pinned to shaft 147 and 148 while crank arm 145' is similarly pinned to a stub shaft 147' axially 30 aligned with shaft 147. Shaft 147' is to the right of and parallel to the shaft 65 and is at its lower end supported by a thrust bearing 149 of identical design as bearing 66 and within the same bearing block 150 as the latter.

35 The upper end of shaft 147 extends into an aperture 151 within the carriage guide plate 28 for proper support and alignment with the center of thrust bearing 148. The greater part of the shaft 147 between the crank arm 145 and the 40 guide plate 28 is of a somewhat increased diameter in contrast to the upper and lower ends thereof. This is done to facilitate mounting of an assembly 152 (Figures 5 and 8) by means of which it is possible to connect the double acting 45 air compressor 141 with the shift actuating mechanism on the shaft 65 during the last step of a shift. This assembly 152 comprises a clutch collar 153 slidably mounted on the enlarged portion of said shaft 147 by means of a pin and slot 50 connection 154 and 155 respectively. The slideable clutch collar 153 is equipped with a pair of upper teeth 156 (Figure 5), diametrically opposite each other and a similar pair of teeth 157 disposed on the lower end thereof. Normally the 55 two teeth 157 engage the two complementary notches 158 in a stationary member 159 fixed to the frame. The central bore 161 of member 159 surrounding the enlarged portion of shaft 147 is of sufficient diameter to accommodate a compression spring 162 which tends to push collar 153 in upward direction to bring its pair of upper teeth 156 into engagement with two diametrically opposed notches 163 in the collar 164 of spur gear 165, supported and freely rotatable on the shoulder 166 formed by the upper end of the enlarged portion of shaft 147.

Such upward movement by collar 153, however, is normally prevented by a cam lever 167 (Figures 4, 5 and 9) pivoted at 168 to a bracket 168a 70 which is attached to the underside of plate 28 and which is provided to prevent operation of the air compressor 141 before the last step of a carriage shift. The free end of cam lever 167 (Figures 5 and 9) is interposed between the two pins 169 and 170 on the collars 164 and 153, respec-

tively, in such a manner that the lower teeth 157 on collar 153 are normally kept in locking engagement with their cooperating notches 158 in stationary member 159 and against the upward pressure exerted on said collar 153 by compression spring 162, thus making it impossible for the collar 153 to move in any direction, as well as making it impossible for the air compressor 141 to function as both of these units are keyed to the shaft 147 and work in unison. This construction excludes any danger of piston 143 making a half stroke, due to the compressed air behind the piston after a carriage stopping operation. Furthermore, it assures perfect alignment and timing of said teeth 156 and 157 with their cooperating notches 163 and 158.

The spur gear 165 is in constant mesh with another larger spur gear 171 twice its size which is rigidly secured to bevel gear 76 on shaft 65 by two pins 172, the ratio being such that each carriage shift step will cause approximately one-fourth rotation of gear 171 and consequently only one-half rotation of gear 165. Since the gear 171 is rotated during each step of a shifting operation, it of course in turn rotates gear 165 a corresponding amount, so that the pair of diametrically opposed pins 169 on collar 164 are also displaced. The moment that the pin 169 which happens to be riding on top of the high point 167c of cam lever 167 is displaced, the latter is free to 30 rock upwardly a sufficient distance to permit engagement by two teeth 156 with their cooperating notches 163 in collar 164 under pressure of spring 162. However, such upward movement of lever 167 is prevented by means hereinafter described until the rotation of gear 165 incident to the last step of movement of the carriage.

It will be noted that notches 163 are somewhat wider than the dogs 156, when viewing Figure 5. This is necessary since gear 165 must first be 40 rotated a small amount to allow pin 169 to move from the high point 167c of cam lever 167 before the latter can move upwardly far enough to permit engagement of said notches 163 by teeth 156. Further rotation of gear 165 causes collar 153 to 45 participate in such movement inasmuch as the lower teeth 158 will be riding over the top edge of stationary member 159, thus locking the slideable clutch collar 153 into engagement with the upper collar 164 of spur gear 165. Collar 153 being 50 keyed to the shaft 147 forces the latter to rotate also, and with it crank arm 145, which in turn operates the piston 143 in double acting compressor 141 through a single stroke.

The resistance offered by the compressor 141 55 to the rotational movement of shaft 147 is commensurate to the force needed for slowing up the movement of carriage plate 38 during the last step in the shifting operation and is transmitted from the compressor unit 141 to the plate 38 through 60 the following parts: 144, 145, 147, 153, 165, 171, 76, 64 and through shaft 65 to gear 67 and finally to carriage plate 38, or if the bevel pinion 76 is idling, through the large bevel gear 82 over to bevel gear 77, through clutch member 64 to shaft 65 65 and from there to spur gear 67 and again through the latter to rack 38a of plate 38.

Just before spur gear 165 has completed its half rotation the two pins 169 and 170 on the opposite side of collar 164 and 153 are brought 70 into contact with cam lever 167 and the latter is rocked downwardly again by this pin 169 during its movement over the cam surface 167a to the high point 167c. Such downward rocking movement of lever 167 causes slideable clutch member 75

- 153 to follow suit to again engage with its lower teeth 157 the complementary notches 158 in stationary member 159, thus locking piston 143 against further operation. This cycle of operation can only be initiated when cam lever 167 is released during the last step of a shift by a component operated only at such time, irrespective of the position of pins 169 which rotate continuously with gear 165.
- 10 The release of lever 167 is controlled by the movement of rocking lever 131 (Figure 4), since this lever is only oscillated by arm 32 at the conclusion of a shifting operation when the lug 36 comes into contact with one of the steps 37 on plate 38, as has been fully explained in the preceding part of this specification.

Rocking lever 131 is provided at its upper end with an appropriate cut out portion 131a (Figure 4) equipped with a double acting cam 131b which normally is disposed with its high point on top of a pin 173 carried by said cam lever 167. It is apparent therefore that as long as rocking lever 131 is in its centralized or ineffective position, as shown in Figure 4, the cam lever 167 is held in its downward position (see Figure 5) in which it keeps slideable clutch collar 153 in locking engagement with stationary member 159 against the pressure exerted by compression spring 162 to the contrary. With lever 167 held in such position, rotation of spur gear 165 and its two pins 169 arranged diametrically opposite each other on the collar 164 will have no effect whatsoever on said cam lever 167. But the moment lever 131 is rocked in either direction by arm 32, pin 173 on lever 167 will move to one side of cam 131b and lever 167 will be free to rock upwardly as soon as the restraining influence of the two pins 169 is removed therefrom, thereby permitting clutch collar 153 to shift into driving engagement with the collar 164 of spur gear 165, forcing the latter to rotate against the action of compressor 141, thus effectively slowing up the movement of carriage plate 38 during the last step of a shifting operation in order to relieve the strain placed on dogs 112 and 113 when they are stopping the carriage.

Operation

The various mechanisms constituting the tabulating shift having been fully explained in the preceding specification, a brief description will presently be given of the sequence of operation of the various parts forming the subject matter of the present invention.

55 Let it be assumed that the operator wishes the accumulator carriage to be shifted from the sixth order, in which it happens to be, to the second order. The operator will then have to depress the shift key representing the number two order of the actuator. This would be the second key from the right hand side when viewing Figures 1 and 2. As the key stem 4 of this key is being pressed downwardly by the operator against the tension of its compression spring 3, the slide 6 is shifted toward the left the number of increments necessary to position the lug 36 on arm 32 in the shifting path of the #2 step or ridge 37 on the bottom face of carriage plate 38. Movement of slide 6 is transmitted to arm 32 by the parts 12, 21, 24, 26 and 30. A mechanical representation of the instant or starting position of the carriage is formed by the position of the ridge 37 in the path of movement of lug 36, and during adjustment of arm 32, in this case, lug 36 will be moved over the #6 ridge 37 with the result that

arm 32 is rocked downwardly for an instant, imparting a similar movement to two-armed rocking lever 34 (Figure 4) pivoted at 35 which with its right hand end underlying nose 45b of lever 45, causes the latter to be raised sufficiently above 5 nose 61 so as to be latched in such raised position by spring biased latch 88.

Thus the preparatory steps in the shifting operation have been initiated during the first part of the downward stroke of the shift key 10 representing the #2 order. These steps consist of forming a mechanical representation of the desired position of the carriage by positioning lug 36 in the path of the #2 ridge 37 for controlling the extent of the shifting operation and the 15 latching of nose 45b in raised position for pre-determining the direction of the ensuing shift.

During the second part of the downward stroke of the #2 shift key, the bail 13 is rocked in clockwise direction about its two pivot points 14 (Figure 7) bringing the rearward projection 15 (Figures 1 and 2) thereof into the proper notch 29a of arcuate rack 29 on the forward end of bell-crank lever 26. At the same time, through downwardly extending arm 16 on bail 13, bellcrank 25 41 (Figure 1) is rotated in counter-clockwise direction, causing two-armed lever 43 to be rotated in clockwise direction, therewith pushing arm 45 and slide 46, to which the former is pivotally attached, a sufficient distance to the left, against the tension of spring 51, so as to be latched by latch 53. This movement removes the restraining influence of the strong tension spring 51 from the coil spring 52 on bail 13, thus permitting the latter to hold projection 15 on bail 13 firmly in engagement with arcuate rack 29 until slide 46 is released again at the completion of the shift. The arm 32 and its lug 36 are therefore maintained in their adjusted positions after the operator releases the #2 shift key.

Two other important operations are instituted during the movement of parts 45 and 46 towards latching position. Nose 45b, which has already been latched in raised position by hook 88a, is moved on top of nose 61a of rocking lever 61, causing the latter to rock against the tension of the centralizer 83 a limited distance in clockwise direction about its fulcrum point 35, and by virtue of its pin and slot connection 62a (Figures 1 and 4) with shift fork 62, this fork is also rotated about its pivot point 63a, but in counter-clockwise direction, with the result that the clutch collar 64 (Figure 5) on shaft 65 is shifted out of its locking or neutral position and into driving relationship with the lower bevel gear 71.

55 Coil spring 96 now unwinds and transmits rotational movement to the shaft 65 and the spur gear 67 through the medium of housing 97, bevel gears 82 and 77 and the clutch collar 64 which is keyed to said shaft 65 by means of a pin 68, while bevel gear 76 is idling. However, shaft 65 cannot commence to rotate until the dogs 112 and 113 (Figure 3) are disengaged from their respective apertures 38b (Figure 6) in carriage support plate 38. This happens almost simultaneously with the operation just described and is effected by the cam 46b through the medium of parts 116, 117, 118, 121, 122, 125 and 126. The timing of these two operations is such that the clutch collar is fully positioned before the dogs 70 112 and 113 are pulled out of engagement with plate 38.

All the parts necessary for predetermining the extent or distance of the shift as well as the direction thereof are now held firmly locked in 75

their effective positions by the slide 46 and the latch 53 and the carriage plate 38 is now free to be shifted by the coil spring 96 from the #6 order to the #2 order, this being in a direction towards the left.

As soon as the carriage plate 38 is shifted through three of the four orders required, step #2 comes into contact with lug 36, placed in its path of operation, and the remaining movement into the #2 order by plate 38 is utilized to stop the latter as well as to restore all the various parts to their initial or normal locations.

Arm 32 is now pushed towards the left by the #2 step on plate 38 and in doing so oscillates lever 131 (Figure 4) which is pivoted at 132 to the bracket 133, in clockwise direction by virtue of its connection 135 and 136 with said lever 131. This oscillation in clockwise direction of lever 131, when viewing Figure 4, releases cam lever 167 so that it can swing upwardly to establish a driving relationship between compressor 141 and shaft 65 to retard the shifting movement of plate 38 during the last step, and also causes centralizer 137 to rock in counter-clockwise direction, which in turn transmits its movement to lever 140 through the shaft 138, to which both of the last mentioned levers are keyed.

The free end of lever 140 resting on top of a lateral extension of latch 53 forces the latter against the tension of its spring 50 to release the slide 46 and consequently all the other parts controlled thereby which are immediately restored to their neutral positions by the spring 51. These parts comprise the dogs 112 and 113, two-armed lever 61, shift fork 62, and clutch collar 64, dogs 112 and 113, clutch collar 64, and gears 76 and 77 serving to stop and lock the carriage in position at the completion of the last step of the shifting operation. Tension spring 9 becomes effective to restore (Figure 2) the slide 6, lever 21, bellcrank 26, and arm 32, which is centralized again to the position shown in Figures 1, 5 and 6 by centralizer 137 and through the medium of rocking lever 131 while the bail 13 is rotated in counter-clockwise direction to again assume its neutral location, such as shown in Figures 2 and 7, by the parts 45, 43 and 41 through the action of the tension spring 51.

In arresting leftward movement of the carriage, lever 32 is moved toward the left as it is viewed in Figures 1 and 6, which is toward the right as it is viewed in Figure 4. This movement carries it out of engagement with the upper end of lever 34 so that the latter will not be relatched in its left shift determining position as the lever 32 passes under ridge 37 during restoration to normal position. A shift of the carriage to the right does not involve movement of the lug 36 past ridge 37 during either setting or restoration, so it is unnecessary to disengage levers 32 and 34 during the stopping operation incident to a shift in this direction.

During the first digitation following this shifting operation, the coil spring 96 (Figure 5) will again be wound up by the parts comprising the friction clutch 99 and by the gear 103 which is geared to the actuator by a train of intermediate gears (not shown).

While the preferred construction has been described in the foregoing specification, it is understood that the invention is capable of modification within the scope of the following claims.

I claim:

1. In a machine of the class described, a stationary mechanism, a displaceable mechanism

having a plurality of operative positions, means movable by said displaceable mechanism, means for shifting said displaceable mechanism in either direction, selectively settable means including a member movable to a plurality of positions corresponding to the respective positions of said displaceable mechanism, and means responsive to said member in movement thereof jointly and concurrently controlled by said movable member and said movable means, and with respect to said movable means to determine the initial direction of operation of said shifting means. 5

2. The combination with a motor driven shiftable carriage, of a plurality of relatively movable members one of which moves synchronously with said carriage and another of which is settable with respect to said first member, means controlled by the relative positions of said members for determining the extent of carriage movement, means controlled by said members jointly 15 for controlling the direction of carriage movement, and means comprising a manipulable member for actuating said direction controlling means and initiating movement of said carriage. 20

3. In a machine of the class described, the combination with a machine frame, a carriage transversely shiftable thereon to a series of operating positions, and motor driven mechanism selectively operable to shift said carriage in either direction to said operating positions; of means 30 movable by said carriage, selectively settable means including a series of keys operable to form a series of mechanical representations corresponding to the respective positions of said carriage, means controlled by said movable means 35 and responsive to said selectively settable means in setting movement thereof to determine the direction of operation of said carriage shifting mechanism, means operable by said selectively settable means for initiating operation of said 40 carriage shifting mechanism, means automatically effective upon initiation of the operation of said shifting mechanism in response to operation of said selectively settable means for latching said shifting mechanism in operating condition, 45 and means controlled by the carriage upon movement to the position represented by the setting of said selectively settable means for disabling said latching means.

4. In a machine of the class described, the combination with a machine frame, a carriage transversely shiftable thereon to a series of operating positions, and motor driven mechanism selectively operable to shift said carriage in either direction to said operating positions; of means 55 movable by said carriage selectively settable means including a series of keys operable to form a series of mechanical representations corresponding to the respective positions of said carriage, means jointly and concurrently controlled 60 by said movable means and responsive to said selectively settable means in setting movement of the latter to determine the initial direction of operation of said carriage shifting mechanism, means operable by said selectively settable means 65 for initiating operation of said carriage shifting mechanism, and means controlled by the carriage upon movement to the position represented by the setting of said selectively settable means for terminating operation of said carriage shifting mechanism. 70

5. In a machine of the class described, the combination with a machine frame, a carriage transversely shiftable thereon to a series of operating positions, motor driven mechanism selec- 75

tively operable to shift said carriage in either direction to said operating positions, and a control device for said mechanism selectively settable to determine the direction of movement of said carriage thereby; of means movable by said carriage means selectively settable to form a series of mechanical representations corresponding to the respective positions of said carriage, and means jointly and concurrently controlled by said movable means and settable in response to said selectively settable means in setting of the latter for controlling adjustment of said control device to predetermine the initial direction of carriage movement.

15. 6. In a machine of the class described, the combination with a machine frame, a carriage transversely shiftable thereon to a series of operating positions, motor driven mechanism selectively operable to shift said carriage in either direction to said operating positions, and a control device for said mechanism selectively settable to determine the direction of movement of said carriage thereby; of means movable by said carriage means selectively settable to form a series of mechanical representations corresponding to the respective positions of said carriage, means jointly and concurrently controlled by said movable means and settable in response to said selectively settable means in setting of the latter for controlling adjustment of said control device to predetermine the initial direction of carriage movement, means for initiating operation of said carriage shifting mechanism, and means controlled by the carriage upon movement to the position represented by the setting of said selectively settable means for terminating operation of said carriage shifting mechanism.

7. In a machine of the class described, the combination with a machine frame, a carriage transversely shiftable thereon to a series of operating positions, and motor driven mechanism selectively operable to shift said carriage in either direction to said operating positions; of means movable by said carriage means selectively settable to form a series of mechanical representations corresponding to the respective positions of said carriage, and means jointly and concurrently controlled by said movable means and settable in response to said selectively settable means in setting movement of the latter to determine the initial direction of operation of said carriage shifting mechanism.

8. In a machine of the class described, the combination with a machine frame, a carriage transversely shiftable thereon to a series of operating positions, and motor driven mechanism selectively operable to shift said carriage in either direction to said operating positions; of means movable by said carriage means selectively settable to form a series of mechanical representations corresponding to the respective positions of said carriage, means jointly and concurrently controlled by said movable means and settable in response to said selectively settable means in setting movement of the latter to determine the initial direction of operation of said carriage shifting mechanism, means for initiating operation of said carriage shifting mechanism and means controlled by the carriage upon movement to the position represented by the setting

of said selectively settable means for terminating operation of said carriage shifting mechanism.

9. In a machine of the class described, the combination with a machine frame, a carriage transversely shiftable thereon to a series of operating positions, and motor driven mechanism operable to shift said carriage; of selectively settable means including a series of keys operable to form a series of mechanical representations corresponding to the respective positions of said carriage, means movable by said carriage, means under the joint and concurrent control of said two means for selectively determining the initial direction and extent of carriage movement, and means comprising said series of keys for initiating movement of the carriage.

10. In a machine of the class described having a frame, and a carriage transversely shiftable thereon to a series of operating positions; the combination with power operated carriage shifting mechanism cyclically operable to shift the carriage from one operating position to an adjacent operating position during each cycle of operation thereof, including a control device and means for preventing operation of said control device to interrupt operation of said mechanism except at the conclusion of each full cycle of operation thereof; of tabulation control means settable to form a mechanical representation of a desired position of said carriage, means for actuating said control device to initiate operation of said carriage shifting means, and means controlled by said tabulation control means and rendered effective upon movement of said carriage to a position within the distance between operating positions in advance of the desired position represented by the setting of said settable control means, for rendering said control device effective to interrupt operation of said carriage shifting mechanism at the conclusion of the current cycle of operation thereof.

11. In a machine of the class described having a frame, and a carriage transversely shiftable thereon to series of operating positions; the combination with power operated carriage shifting mechanism cyclically operable to shift the carriage from one operating position to an adjacent operating position during each cycle of operation thereof, including a control device and means for preventing operation of said control device to interrupt operation of said mechanism except at the conclusion of each full cycle of operation thereof; of tabulation control means settable to form a mechanical representation of a desired position of the carriage, means for actuating said control device to initiate operation of said carriage shifting means, and control means for said carriage shifting mechanism operable to cause the same to shift said carriage from any of said operating positions to a position within the distance between operating positions in advance of the desired position represented by the setting of said settable control means and to thereupon render said control device effective to interrupt operation of said carriage shifting mechanism at the conclusion of the current cycle of operation thereof.
